UNITED STATES PATENT OFFICE.

JOHN O. NEIKIRK, OF LOMBARD, ILLINOIS, ASSIGNOR TO RODGER BALLAST CAR COMPANY, A CORPORATION OF MAINE.

FREIGHT-CAR.

1,248,890.

Specification of Letters Patent.

Patented Dec. 4, 1917.

Application filed February 12, 1917. Serial No. 148,144.

To all whom it may concern:

Be it known that I, JOHN O. NEIKIRK, a citizen of the United States, residing at Lombard, in the county of DuPage and State of Illinois, have invented certain new and useful Improvements in Freight-Cars, of which the following is a specification.

My invention relates to freight cars and has for its general object to improve this 10 type of car and simplify its construction, to increase its carrying capacity and to adapt the car for various kinds of utility. These and other objects will more fully appear in the description hereafter.

15 In the drawings which show an exemplification of my improved car, Figure 1 is a longitudinal section of a portion of the car. Fig. 2 is a cross section on the line 2—2 of Fig. 1. Fig. 3 is a plan view. Fig. 4 is a 20 cross section showing modified arrangement.

The great increase in the transportation of freight during recent years has necessitated the adoption by railroads of cars of much larger carrying capacity than were 25 formerly in use. Fifty tons is now practically the normal capacity of most freight cars, and the tendency is to increase this capacity to seventy tons, even in some instances to ninety tons. This increase has required a much heavier type of equipment, not only in cars but in locomotives, so that 30 it is now common practice to haul long trains of these heavily loaded cars over the roads. This has necessitated reconstruction 35 of the roadbed and requires constant attention to keep the roadbed in proper condition.

By my invention, I seek to provide a car which shall have the required strength, which will carry a greater lading without 40 increase in the size of the car, or which will carry normal lading in a car of shorter length and to provide a car which may readily be adapted to discharge its load practically automatically, and to discharge the 45 load in such a way as to make the car useful for ballast and construction work.

In the drawings, A indicates the center sill of the car. In the exemplification of my invention shown, this is the steel longitudinal member of the underframe, and takes the severe buffing and pulling strains which modern practice imposes upon cars of this type. B are the cross members attached to the center sill and extending therefrom to 55 the sides of the car. There are a number

of these cross members between the body bolsters. C indicates the body bolsters, D indicates the sides of the car, shown in this instance as plate girder sides, which carry the load imposed upon the car and transmit 60 it to the bolsters. These load carrying members are of sufficient strength to take the heavy burdens imposed upon cars of this type, and are so simple in arrangement as to greatly reduce the cost of construction in 65 the shop and of maintenance. The center sill and cross members act as transmitting members. The cross sills are securely riveted to the center sill, which may be of any suitable construction. I have shown a center sill comprising channel beams with the usual cover plate. I have shown in the present exemplification the center sill with parallel upper and lower edges so that the top and bottom of this sill are in parallel 70 horizontal planes. The lower edges of the cross sills are also substantially in the same horizontal plane as the lower edge of the center sill. The same is true of the lower edge of the plate girder sides. By means of 75 this construction I am enabled to use girder sides of maximum depth and of correspondingly great strength without increasing the height of the car sides. This is an important feature as will be hereinafter pointed out. 80 The floor of the car between the end sills and the cross sill adjacent the trucks is formed of horizontal plates E attached to the upper sides of the bolsters, end sills, and adjacent cross sill. The entire floor of the 85 car between the trucks is formed of horizontal plates F attached to the under edges of the center sills and underframe members. By means of this construction I have provided a car in which the center of gravity 90 is lowered, thus making the car safer and less liable to derailment, and I have increased the load carrying capacity of the car very materially. For example, a forty one foot general service gondola car has a normal capacity of approximately fifty tons 95 with an overload capacity of fifty five tons, while a forty one foot car with the floor arranged as herein described has a carrying capacity of approximately sixty four tons 100 with an overload capacity of nearly seventy tons. That is to say, the carrying capacity of the same length car is greatly increased, while with my improved construction in 105 order to carry a load of fifty tons with over 110

load of fifty five tons, it is possible to decrease the length of the car from forty one feet to approximately thirty four feet six inches. This saving is of great importance 5 both in the cost of construction, in the saving of weight to be hauled, and in the saving in the length of trains.

In order to rapidly discharge the load, the 10 floor of the car between the trucks may, instead of being rigidly attached to the under side of the underframe, be made in the form of doors as indicated by F' in Fig. 4 of the drawing. These doors would extend the 15 full length of the space between the cross sills adjacent the trucks and may be hinged at or near the center sill, as indicated in Fig. 4, extending out to the sides of the car. Any suitable form of operating device may 20 be employed for opening and closing the doors. I have indicated diagrammatically a chain and winding shaft, it being understood that the chain and winding shaft will be operated by any of the well known mechanisms attached to the end of the winding 25 shaft. I prefer a mechanism such as shown in Meissner Patent No. 716,075 dated December 16th, 1902, by means of which the descent of the doors may be controlled.

Prior to my invention, it has been customary 30 to hinge the doors of what are known as general service cars to the upper edges of the center sill, or adjacent thereto. Owing to the necessary presence of the cross members in cars of this type, it has been 35 necessary in these general service cars to employ a door between the adjacent cross members so that the floor of the car has consisted of a number of doors extending either from end to end of the car between the bolsters or between the trucks, as the case may 40 be. As these cars are adapted to carry not only loose material, which may be dumped, such as coal, gravel, crushed rock, etc., but are also used for carrying concentrated 45 loads, such as heavy machinery or heavy package freight as well as rails, billets, or, in fact, any material which may be carried in a gondola car, it has sometimes happened 50 that extremely heavy concentrated loads have been placed upon the doors of these general service cars, which doors and mechanism for operating them have not been especially designed for carrying such loads.

It will be noted that in my improved car 55 the underframe members between the trucks are exposed so that a concentrated load will not be placed upon the horizontal floor of the car between the trucks, but such load will rest upon the upper surface of the underframe members. Owing to the position of the doors and their hinges, I am enabled to construct a car through which the 60 load may be discharged to greater advan-

tage than in the general service cars hitherto used in which the doors are hinged on the upper side of the center sill, since with doors hinged as hereinbefore described a door of the same length will discharge its 70 load entirely outside the rails. My car is thus especially well adapted for depositing the ballast at the sides of the track, or for depositing coal through the side openings in trestles. 75

Another advantage of the construction herein described whether with the doors or with the fixed bottom is, that a girder side of maximum depth and corresponding strength may be used without increasing the 80 height of the car side. This is of special importance in cars in which the doors are used, since in general service cars in which the doors are hinged to the top of the center sill it has been necessary that the lower edge 85 of the car side should be in substantially the same plane as the top of the center sill in order to afford a sufficient opening for the discharge of material. With my improved 90 construction I provide the same size of opening and at the same time enable the lower edge of the side to be brought down to substantially the level of the lower edge 95 of the center sill.

A further advantage of my car is, that by placing the floor beneath the underframe between the trucks, I am enabled to use doors extending the entire length of the space between the trucks in place of using 100 a door between adjacent cross sills. This reduces the leakage of fine material to a minimum. These and other advantages of my improved construction will be apparent to those skilled in the art. While I have shown and described one exemplification of 105 my invention, I do not wish to be understood as limiting my invention beyond what is claimed.

What I claim is:

1. A car of the class described having an 110 underframe comprising a center sill taking the draft and buffing strains, cross members extending from the center sill to the car sides, a substantially horizontal floor for said car extending between the trucks, said floor consisting of a single door on each side of the center sill hinged to the center sill below the cross members and extending from the center sill entirely beneath at least one 115 of the cross members and toward the sides of the car.

2. A car of the class described having an 120 underframe comprising a center sill taking the draft and buffing strains, cross members 125 extending from the center sill to the car sides, a substantially horizontal floor for said car, that portion of the floor intermediate the trucks being in a lower plane than the end portions of the floor, said in- 130

termediate portion being connected to the center sill and extending therefrom entirely beneath at least one of the cross members and toward the car sides.

5 3. A car of the class described having an underframe comprising a center sill taking the draft and buffing strains, cross members extending from the center sill to the car sides, substantially horizontal floor portions 10 extending over the trucks, an intermediate

floor portion extending between the trucks below the plane of the end portions, said intermediate portion comprising doors hinged to the center sill and extending therefrom entirely beneath at least one of the cross 15 members and toward the car sides.

JOHN O. NEIKIRK.
